(57) **CLAIM**

The ornamental design for pair of gloves, as shown and described.

DESCRIPTION

FIG. 1 is an elevational palm-side view of a right hand glove according to a first embodiment of the present invention; FIG. 2 is an elevational backhand view of the glove of FIG. 1 according to the present invention;

FIG. 3 is an elevational palm-side view of a left hand glove according to the first embodiment of the present invention; FIG. 4 is an elevational backhand view of the glove of FIG. 3 according to the present invention;

FIG. 5 is an elevational palm side view of the glove of FIGS. 1 and 2 being worn by a user according to the present invention;

FIG. 6 is an elevational backhand view of the glove of FIGS. 1 and 2 being worn by a user according to the present invention;

FIG. 7 is an elevational palm side view of the glove of FIGS. 3 and 4 being worn by a user according to the present invention;

FIG. 8 is an elevational backhand view of the glove of FIGS. 3 and 4 being worn by a user according to the present invention.

FIG. 9 is an elevational palm-side view of a right hand glove according to a second embodiment of the present invention; FIG. 10 is an elevational backhand view of the glove of FIG. 9 according to the present invention;

FIG. 11 is an elevational palm-side view of a left hand glove according to the second embodiment of the invention; FIG. 12 is an elevational backhand view of the glove of FIG. 11 according to the present invention;

FIG. 13 is an elevational palm side view of the glove of FIGS. 9 and 10 being worn by a user according to the present invention;

FIG. 14 is an elevational backhand view of the glove of FIGS. 9 and 10 being worn by a user according to the present invention;

FIG. 15 is an elevational palm side view of the glove of FIGS. 11 and 12 being worn by a user according to the present invention; and,

FIG. 16 is an elevational backhand view of the glove of FIGS. 11 and 12 being worn by a user according to the present invention.

The partial human figure shown in broken lines in the figures illustrates the environment in which the claimed design is used and forms no part of the claimed design. The stippling in the drawings represents contrasting color.
